UNITED STATES PATENT OFFICE.

THOMAS CASCADEN, JR., OF WATERLOO, IOWA, ASSIGNOR TO THE DAVIS GASOLINE ENGINE WORKS COMPANY, OF SAME PLACE.

STEAM-GENERATOR.

SPECIFICATION forming part of Letters Patent No. 665,062, dated January 1, 1901.

Application filed June 7, 1900. Serial No. 19,462. (No. model.)

To all whom it may concern:

Be it known that I, THOMAS CASCADEN, Jr., a resident of Waterloo, in the county of Black Hawk and State of Iowa, have invented certain new and useful Improvements in Steam-Generators, of which the following is a full, clear, and exact description.

This invention has relation more particularly to that class of steam-generators more particularly adapted for the steaming and cooking of food for cattle, or like situations, where the generation of the low pressure of steam is desired. Manifestly, however, the improvements hereinafter described may be employed in other types of steam-generators without departing from the spirit of the invention.

In the construction of low-pressure steam-generators such as are commonly used for the steaming and cooking of cattle-food it is desirable in order to meet the demands of the trade that the construction of the generator shall be as simple and cheap as is consistent with safety. The most common of this type of steam-generators is that form in which the body of the generator is of oval shape, the lower part, which comprises the fire-box, being separated by a simple crown-sheet from the upper part, that comprises the boiler, and the charging-door of the fire-box being at the front of the generator and the smoke-stack at the rear.

The main object of this invention is to provide a far more effective steam-generator at a comparatively slight increase in cost; and this object I have accomplished, first, by the improvement in the construction of the generator so that the water-spaces shall extend at each side of the fire-box, and, second, by providing a water-pan that is located in the fire-box and is in communication with the main water-chamber of the generator, this pan being preferably so disposed as to cause the products of combustion to travel to the back of the fire-box and to be then returned to the front, at which point the smoke-stack is located.

Referring to the accompanying drawings, Figure 1 is a view in elevation of the steam-generator with parts broken away and parts in cross-section. Fig. 2 is a view in cross-

section on line 2 2 of Fig. 1. Fig. 3 is a partial view in cross-section on line 3 3 of Fig. 1, and Fig. 4 is an enlarged sectional view of the water-pan.

55

The body of the generator, which is preferably formed of plate-steel, (fourteen gage being a suitable thickness,) comprises the outer casing A, the inner casing B, the back plate C, and the front plate D. The outer shell or casing A is united to the inner shell or casing B by suitable bolts E, and these bolts at the rear end of the generator also pass through the outwardly-turned flanges c of the front and back plates. By preference, 60 also, reinforce-straps F extend around the front, rear, and sides of the generator, and through these straps the bolts E also pass. By reference to Figs. 1 and 2 of the drawings it will be seen that the inner casing B, 70 the upper part of which constitutes the crown-sheet of the generator, is extended down to the bottom of the generator and forms with the outer casing a downwardly-narrowing chamber at each side of the fire-box H. The 75 space between the inner and outer casings A and B constitutes the water-chamber, and hence it will be seen that a thin sheet of water is exposed to the action of the heat at each side of the fire-box. By thus forming 80 the sides of the generator with double walls a much more extended area of water-surface is exposed to the action of the products of combustion, so that the effective heat of the fuel is more fully attained. The interior of the casing B, which comprises the fire-box and combustion-chamber of the generator, is provided in its front portion with suitable grate-bars J, 85 upon which the fuel will be laid. Within the combustion-chamber, and preferably in the 90 location shown in the drawings, is placed a water-pan that serves a twofold function—first, to cause the products of combustion to pass in rearward and then in forward direction until they escape by the smoke-stack S, 95 that is located at the top of the front of the fire-box, and, second, to expose a large thin body of water to the action of the products of combustion within the fire-box. As shown, this water-pan consists of a cast-metal 100 body M, having a flange m, to which is connected by bolts N the bottom plate O. Pref-

- erably this bottom plate is of plate-steel, the holes therethrough being drilled coincident with corresponding holes that will be cast in the flange of body M of the water-pan.
- 5 Preferably a strip of asbestos packing material m' is placed between the edges of plate O and flange m , and a reinforcing-strap F', similar to strap F, is placed between the edges of plate O and the nuts on 10 bolts N. Preferably, also, the water-pan is of substantially the full width of the fire-box and is connected at its inner end to the casing B by short threaded coupling-pipes P, that enter threaded holes in the sides of the pan 15 M and also enter corresponding holes in the side walls of the casing B, suitable retaining-nuts p being employed upon the outer ends of the coupling-pipes P to securely clamp the side wall of the casing B to the water-pan M.
- 20 The upper end of the water-pan is preferably connected to the top or crown-sheet of the casing B by a short pipe R, the lower threaded end of which is united to the top of the water-pan by suitable threaded nuts r ,
- 25 while the upper end of this pipe R is connected to the crown-sheet of the casing B by corresponding threaded nuts r' , arranged upon opposite sides of the crown-sheet. If desired, also, bolts t may be passed through 30 the front wall D of the heater and into the end of the water-pan M. It will be understood, of course, that the front of the heater will be provided with the usual charging-door, whereby fuel will be admitted to the fire-box,
- 35 and the rear of the generator will be furnished with pump and gage-cocks as desired, and the top of the generator will be provided with the usual dome and steam-supply pipe leading therefrom.
- 40 From the foregoing description it will be seen that in a steam-generator embodying my improvements not only is a very much larger surface of water exposed to the action of the heat within the fire-box by reason of the double walls at the sides thereof, but inasmuch as the products of combustion are caused to be returned to the front of the generator before their escape to the smoke-stack a much more effective utilization of the heat is attained. Moreover, as the products of combustion pass around the water-pan located 45 above the fire-box the thin sheet of water within this pan is exposed to a high temperature, and by reason of its communication with 50 the body of water above the crown-sheet of

the boiler the heating of the water and the rapid generation of steam are effectively accomplished.

By reference to Fig. 1 of the drawings it will be seen that the water-pan is inclined 60 downwardly from the front toward the rear, the purpose of this arrangement being not only to allow circulation of water through the pan and the draining of the same, but also to cause the more effective action of the products of combustion upon the pan as they travel toward the back and are returned to the front of the combustion-chamber. In order to enable the water-chamber to be effectively drained, suitable holes w will be provided at the rear of the water-chamber adjacent its bottom, these holes being normally closed by suitable plugs.

It is manifest that the precise details of construction above set out may be varied without departing from the spirit of the invention.

Having thus described my invention, what I claim as new, and desire to secure by Letters Patent, is—

In an internally-fired steam-boiler, the combination with inner and outer shells forming an internal-combustion chamber, a water-space and water-legs on either side of the combustion-chamber directly connected with the water-space, of a fire-box and smoke-stack 85 at the forward end of the combustion-chamber, a water-pan having a closing-plate bolted thereto arranged in the internal-combustion chamber between the fire-box and smoke-stack and preventing direct communication 90 between the two, said water-pan extending from the forward end of the combustion-chamber and downwardly inclined toward the rear end, threaded nipples connecting the lower rear end of said water-pan and the inner shell and opening into and forming communications between said water-pan and the water-legs on either side of the combustion-chamber, and a threaded pipe connecting the upper, front end of the water-pan and the 100 upper part of the inner shell or crown-sheet, lock-nuts on said pipe and said nipples on either side of the inner shell, whereby a return draft under and over the water-pan and a ready circulation of the water through the 105 pan are produced.

THOMAS CASCADEN, JR.
